SIGN

John S. Van Ausdall, Oak Park, Ill., assignor to
Advertising Posters Company

Application January 30, 1939, Serial No. 253,535

2 Claims. (Cl. 40—132)

The present invention relates to signs, and particularly to illuminated display devices wherein a display panel is provided with a display pattern and a lamp behind the panel is utilized for illuminating certain parts of the pattern. In devices of this character it is customary to utilize opaque and more or less transparent coatings for the purpose of delineating the display pattern. The display pattern may, of course, take a great variety of forms. It may consist entirely of a legend, or may be composed partially of a legend and partially of a pictorial representation, or may be entirely of a pictorial representation.

It is the principal purpose of this invention to provide a device of this character whereby novel illuminating effects may be obtained with the usual stationary or moving light source. By moving light source I mean a light source which directs a moving band of light across the panel. A typical device embodying the present invention may constitute a lamp, a casing for the lamp and a display panel mounted in said casing in spaced relation to the lamp. A light screen may, in certain forms of the invention, be placed between the lamp and the panel, and this light screen may contain various light obstructing portions whereby to cause moving bands of light to pass in certain directions across the rear of the display panel. The present invention is directed particularly to modification of the panel structure, whereby to obtain a novel cooperation with the lamp and the light screen.

The features and advantages of the present invention will appear more fully as the description proceeds, reference being had to the accompanying drawing wherein a preferred form of the invention is shown. It is to be understood, however, that the drawing and description are illustrative only, and are not to be taken as limiting the invention except insofar as it is limited by the claims.

In the drawing, Fig. 1 is a somewhat diagrammatic front view of a display sign embodying the invention;

Fig. 2 is a transverse section taken substantially on the line 2—2 of Fig. 1;

Fig. 3 is an enlarged fragmentary sectional view taken on the line 3—3 of Fig. 2;

Fig. 4 is a fragmentary view of the front layer of the display panel;

Fig. 5 is a fragmentary view of the rear layer of the display panel shown in Fig. 3;

Fig. 6 is a fragmentary sectional view through a three layer display panel, and

Fig. 7 is a fragmentary view showing the sur-

face of the display panel illustrated in Fig. 6.

Referring now to the drawing, the present invention is embodied in a display advertising device, which, for purposes of illustration, is shown as composing a casing 10 which is made up of a base 11, a housing member 12 and a front panel 13. Within the casing 10 I mount a lamp 14. This lamp may be separated from the front panel 13 by a moving light screen such as shown at 15. In the present invention, the light screen 15 is illustrated as a cylinder having spaced spirally running lines 16 of substantial width, these lines 16 being covered with an opaque coating. The spaces between the lines 16 are desirably translucent, although they may be colored with a suitable translucent coloring matter such as is well-known in the industry.

The moving screen 15 is supported upon a standard 17 so that it may be caused to rotate by the flow of air upwardly around the lamp 14. For this purpose, the top of the cylindrical screen 15 is closed by a cover 18 that has vanes 19 formed thereon, the vanes 19 being cut out of the material of the cover and turned upward at an angle so that air flowing through the openings 25 will strike the vanes and develop enough force to turn the screen 15.

It will be understood that the above mechanism describes only one form of device for creating travelling streaks or pencils of light. Any suitable power means other than that described may be used.

Referring now to the construction of the front panel 13, this construction is illustrated best in Figs. 3, 4 and 5. It will be noted that the panel 35 is made up of two layers 20 and 21, although I do not limit myself to two layers. A larger number may be used. The surfaces 22 and 23 of the layers 20 and 21 are roughened so that each is provided with a multiplicity of lenses in the form 40 of dome-like projections. The layers 20 and 21 are made of glass and desirably the projections are formed in molding the glass. The projections or lenses on the layer 20 are indicated by the numeral 24, while those on the layer 21 are 45 numbered 25. The surfaces of the layers 20 and 21 which are nearest the light source are smooth and flat. These surfaces are used for the purpose of applying pattern delineating coatings of the particular type desired. For example, in Fig. 50 3, I have shown such a coating at 26 in the form of an opaque paint, while at 27 I have indicated a colored translucent coating, and at 28 I have indicated an absence of coating between the two layers 20 and 21. The coatings may be arranged 55

so that the pattern is formed by that part 28 which is devoid of coating. An outline around the pattern or an addition to the pattern may be produced by the translucent colored coating 27 5 and the coating 26 may darken the balance of the surface to form a background.

It will be noted from an examination of Figs. 3, 4 and 5 that the projections 24 on the layer 20 are much larger than the projections 25 on the layer 21. I find this particularly advantageous in conjunction with the moving light screen 15 to produce unusually attractive illusions of movement on the surface of the display panel. As the light bands pass across the panel, the 10 light rays are, of course, directed through the rear layer 21 at a continuously changing angle. The diagonal arrangement of the lines 16 on the cylinder 15 causes vertical and horizontal shifting of the light bands. The light in passing from 15 the small lenses or projections 25 is deflected, and, in passing from the large lenses 24 on the front layer 20, the light will be further deflected. The resulting effect is that the relatively slow motion of the light band traveling across the 20 display panel is translated into a very rapid apparent movement of light as seen from the front of the display panel. The direction of the light shifts continuously, owing to the difference in the angles at which the light rays from the small 25 projections 25 strike the front panel and are directed from the large projections 24. The resulting effect is a shimmer, or dancing light, over the illuminated part of the display panel.

Referring now to Figs. 6 and 7, I have illustrated here a three layer display panel, and I have further indicated the use of pattern delineating coatings in a particularly advantageous manner. A front panel 30 has a roughened front surface 31 and a smooth rear surface 32. The 30 smooth rear surface is coated with a translucent coating 33 which may be, for example, blue in color. A pattern delineating opening 34 is left in the blue coating. A second layer 35 also has a roughened surface indicated at 36 which faces forward. The rear surface 37 of the layer 35 35 has a blue translucent coating 38 thereon and a pattern delineating coating 39 which may be orange in color, for example. A red border coating 40 is provided between the orange 39 and the blue 38. A rear layer 41 also has a roughened front surface 42 and it has a rear opaque coating 43 on its smooth rear surface. The opaque coating 43 is removed to provide a pattern at 44. The

roughening of the front faces of the layers 30, 35 and 41 may be of any suitable type, such as that shown in Figs. 4 and 5, but desirably it is of a random pattern, such as shown in Fig. 7, so that the projections and recesses do not match 5 up in the several layers. When illuminated from the rear, this multiple panel arrangement spreads the light passing through the clear opening 44 so as to illuminate the entire front of the panel, the general illumination being, of course, through 10 the blue coatings 38 and 33. The pattern opening 34, however, in the blue coating 33 will receive most of the direct light entering the clear opening 34 and will thus be much more brilliant than the rest of the panel. The color of the pattern 15 will, of course, correspond to the coloring of the orange layer 39 and any border deflection of light due to the roughening of the surfaces of the layers 35 and 41 will be shaded by the border coating 40. 20

Having thus described my invention, what I claim as new and desire to secure by Letters Patent is:

1. A display advertising device comprising in combination a casing, a lamp therein, a display 25 panel, said display panel comprising a plurality of layers of glass, each layer having its surface remote from the lamp covered with hills and valleys of substantial magnitude, and its surface nearest the lamp smooth, the layer closest the 30 lamp having an opaque coating on its smooth surface, said coating being absent over a portion of the surface to produce a display pattern, and each layer farther from the lamp than said first named layer having a translucent coating on its 35 smooth surface, said coating on at least one layer being arranged to produce said display pattern in alignment with the pattern on said first named layer.

2. A display advertising device of the character 40 described comprising a front glass plate having its front face formed with a multiplicity of hills and valleys of substantial magnitude, a second glass plate in rear of said first plate and having one face provided with a multiplicity of lenses, 45 a light source in rear of said second plate and means for varying the angle of light to the individual lenses on said second plate whereby to produce a dancing light effect from the front plate, said front plate having a smooth rear face 50 and a pattern delineating coating on said rear face.

JOHN S. VAN AUDSALL.
